UNITED STATES PATENT OFFICE.

EDD C. OLIVER, OF MINNEAPOLIS, MINNESOTA, ASSIGNOR TO HARRY E. PENCE, OF MINNEAPOLIS, MINNESOTA.

SPEED-INDICATOR.

No. 870,795.

Specification of Letters Patent.

Patented Nov. 12, 1907.

Application filed November 13, 1906. Serial No. 343,238.

To all whom it may concern:

Be it known that I, EDD C. OLIVER, of Minneapolis, Hennepin county, Minnesota, have invented certain new and useful Improvements in Speed-Indicators, of which the following is a specification.

The object of my invention is to improve the construction and cheapen the cost of manufacturing the indicator described in my pending application No. 328,831, filed Aug. 2, 1906.

10 A further object is to provide an indicator which can be assembled without fine adjustments and without the necessity of calibrating each instrument.

15 A further object is to provide an indicator which can be easily adjusted to compensate for wear or changes of temperature.

The invention consists generally in various constructions and combinations, all as hereinafter described and particularly pointed out in the claims.

20 In the accompanying drawings, forming part of this specification, Figure 1 is a sectional view of a speed indicator embodying my invention. Fig. 2 is a detail sectional view showing the position assumed by the parts when the device is in operation, the casing being removed.

25 In the drawing, 2 represents a suitable casing wherein the operating mechanism is arranged.

30 3 is a vertical shaft connected by any suitable means as a flexible shaft (not shown) with a wheel of the automobile or with a moving part of a piece of stationary mechanism on which the instrument may be used.

35 This shaft has ball bearings 4 at each end and a longitudinal slot 5 inclosed by an oscillating ring 6. This ring, as indicated in Fig. 1, occupies a position normally at an acute angle with respect to the longitudinal

40 axis of the shaft, with its axis, however, coinciding with the center of the shaft so that the center of mass of the ring remains throughout its entire movement at the center of rotation. When the shaft is revolved the ring will oscillate by centrifugal force and swing on its pivot

45 toward a horizontal position, as indicated in Fig. 2. The shaft 3 has a socket 7 below the slot 5 with a coil spring 8 fitting therein, the tension of which is regulated by a set screw 9 mounted in the said shaft at one end of the socket, and engaging the end of the spring. A

50 pin 10 has a flange 11 in engagement with the other end of the spring and said pin is pivoted on the short arm of a bell crank 12 that is pivoted at 13 on the shaft. The long arm of the bell crank 12 projects through the slot 5 and is adapted to bear on the cam surface 14 of a

55 plate 15 that is secured on the inner surface of the ring 6 by any suitable means, as a set screw 16. The movement of the ring is transmitted to a suitable indicating device through the link 17 and arm 18 mounted on a vertically movable pin 19, the travel of said pin being

55 transmitted to the indicator hand by a mechanism sub-

stantially the same as shown in my application above referred to and which will need no further illustration herein.

The coil springs 8 can be made of substantially uniform tension and a large number of them turned out 60 with but little variation in power and movement, and the force exerted by such a spring on the short arm of the bell crank will be commensurate with the movement of the arm. I have therefore found this form of spring superior to the flat one employed in my earlier 65 application, as it was difficult to make the flat springs uniform in tension and their movement would not be entirely commensurate with the pressure exerted on the cams, and hence it became necessary to calibrate each instrument separately to determine its degree of 70 accuracy. By the use of the bell crank and the coil however, I have avoided all fine adjustments, the bell spring, crank and springs can all be made alike and be interchangeable, and the instruments can be put together and adjusted for use without ascertaining the 75 tension of each spring separately or calibrating each instrument.

With this device, as in the one shown in my former application the center of mass of the ring does not travel away from the center of rotation of the shaft 80 which is also the center of oscillation of the weight, hence the shaking or jarring incident to rough roads or streets will have no vibratory effect on the indicator hand. The device will have the same efficiency for indicating low speeds as the other instrument. 85

It will be noted that the effective leverage of the spring on the cam varies with the speed of rotation of the spindle, and also that the tension of the spring increases with the speed of rotation. 90

I claim as my invention:

1. In a speed indicating device, the combination, with a rotating spindle, of a weight centrally pivoted thereon and having a cam surface, a spring, a lever bearing on said spring and on said cam surface, the effective leverage of the spring on the cam varying with the speed of rotation. 95

2. In a speed indicating device, the combination, with a rotating spindle, of a ring pivoted thereon, the center of mass of said ring remaining substantially at the center of rotation during the oscillation of said ring, a cam mounted on said ring, a compression spring, a lever mechanism for transmitting the pressure of said spring to said cam, the effective leverage of the spring on the cam varying with the speed of rotation. 100

3. In a speed indicating device, the combination, with a rotating-spindle, of a weight pivoted thereon and having a cam surface, a lever having one arm in engagement with said cam surface, and a spring in engagement with the other arm of said lever, the tension of said spring increasing with the speed of rotation, substantially as described. 105

4. In a speed indicating device, the combination, with a rotating spindle, of a weight centrally pivoted thereon and having a cam surface, a bell crank having one arm in engagement with said cam surface, a compression

spring in engagement with the other arm of said bell crank, means for adjusting said spring, and the compression of said spring increasing with the speed of rotation.

5. The combination, with a rotating spindle having a slot therein, of a ring centrally pivoted on said spindle and having a cam surface, an indicating device, a bell crank pivoted on said spindle and having one arm projecting through said slot and in engagement with said cam surface and a coil spring fitting within a socket in said spindle having one end in engagement with the other arm of said bell crank, substantially as described.

6. In a speed indicating device, the combination, with a rotating spindle, of a ring pivoted thereon, a cam mounted 15 on said ring, a compression spring arranged at an angle to the axis of said spindle, a means for transmitting the pressure of said spring to said cam, the effective leverage of the spring on the cam varying with the speed of rotation, substantially as described.

10. 7. In a speed indicating device, the combination, with a rotating spindle, of a weight pivoted thereon having a cam surface, a lever pivoted at a point intermediate to its ends and having one arm in engagement with said cam surface, a spring arranged to engage the other arm 20 of said lever, the distance between the bearing point of said spring on said lever and the pivot of the lever re-

maining constant while the distance between the pivot of said lever and the point of contact of the other arm with said cam varies with the speed of rotation, substantially as described.

30 8. In a speed indicating device, the combination, with a rotating spindle, of a weight pivoted thereon and having a cam surface, a coil spring and a lever device bearing on said spring and on said cam surface.

9. In a speed indicating device, the combination, with a rotating spindle, of a weight pivoted thereon and having a cam surface, a compression spring, and a single lever arranged to transmit the motion of said cam to said spring.

10. In a speed indicating device, a rotating spindle in 40 combination with a weight pivoted thereon, said weight having a cam surface, a lever arranged to engage said surface, and be actuated by the movement of said weight and cam, and means for yieldingly holding said lever in engagement with said surface.

45 In witness whereof, I have hereunto set my hand this 6th day of November 1906.

EDD C. OLIVER.
